UNITED STATES PATENT OFFICE.

HAROLD F. SHEPHERD, OF GROVE CITY, PENNSYLVANIA, ASSIGNEE TO BESSEMER GAS ENGINE COMPANY, OF GROVE CITY, PENNSYLVANIA, A CORPORATION OF PENNSYLVANIA.

SHAFT-GOVERNOR.

1,164,021.

Specification of Letters Patent. Patented Dec. 14, 1915.

Application filed August 12, 1914. Serial No. 856,383.

To all whom it may concern:

Be it known that I, HAROLD F. SHEPHERD, a citizen of the United States, residing at Grove City, in the county of Mercer and State of Pennsylvania, have invented new and useful Improvements in Shaft-Governors, of which the following is a specification.

This invention relates to shaft governors and consists in certain improvements in the construction thereof as will be hereinafter fully described and pointed out in the claims.

While the governor illustrated is applicable to different devices in which a shaft 15 governor is desired, it is particularly desirable in handling fuel injectors for oil engines where the thrust on the rods controlled by the governor extend through a comparatively short period but is large during this 20 period. It is also particularly desirable where comparatively light fly wheels are used wherein there are momentary changes in velocity and it is desirable to have sufficient mass of the governor to take care of 25 the thrust, yet so arranged as to centrifugal force as to be stable under the momentary changes in velocity referred to.

The invention is illustrated in the accompanying drawing wherein 1 marks the crank 30 shaft, 2 the fly wheel and 3 the hub of the fly wheel.

The centrifugal weight is ring shaped and encircles the axis of the carrier formed by the fly wheel 2 and also the hub of the fly 35 wheel or carrier.

The weight 4 is pivoted on a pin 5 mounted on the fly wheel.

A spring 6 forms the centripetal element of the governor.

40 Stops 7 are provided to limit the movement of the weight and the dash pot 8 is provided. The eccentric rod 9 which extends to whatever mechanism it is desired to actuate and control is connected with the 45 eccentric strap 10.

The eccentric strap is mounted on the eccentric 11.

The eccentric 11 is carried by a swinging mounting 12. The swinging mounting 12 is 50 pivotally supported on a pin 13, the pin extending from the fly wheel 2. The mounting 12 has an extension 14. This is connected by a pivotal and sliding connection with the weight, this connection being formed as follows: A pin 15 projects into and through

the extension 14. It is carried by a sliding block 16. The block 16 is slidably mounted between the guide fingers 17. The guide fingers 17 are secured one at each side of a lug 18 extending from the face of the 60 weight 4. The guide fingers are secured to the lug by the bolt 19.

The weight of the eccentric, eccentric strap and immediately connected parts is such that acting through the swinging 65 mounting 12 on the pin 13 as a fulcrum it will balance the centrifugal weight 4 so that by this simple expedient the governor is balanced as to gravity.

It will be observed that the line of strain 70 between the eccentric rod 9 and the eccentric as the rod 9 is reciprocated by the eccentric extends in the general direction X—X and that the axis of the pivotal support 13 passes through this line of strain during the faster 75 portion of the throw of the eccentric and preferably the axis of the pin 13 passes through this line of strain with the eccentric approximately on quarter. As a result of this arrangement, the thrust or pull upon 80 the rod 9 has its tendency to throw the eccentric toward and from the center reversed while moving in the same direction, that is, while having the pull or thrust. Furthermore, the greatest strain ordinarily being 85 at the quarter is almost directly in line with the pivotal support so that the tendency to throw the eccentric is largely neutralized.

By making this centrifugal weight ring shaped it is possible to place its center of 90 gravity within the limits of the hub yet have a very large mass for the weight. In this way, the centrifugal force is diminished relatively to the mass of the weight, yet the weight has sufficient mass to withstand the 95 momentary disturbances to which the governor is subjected.

What I claim as new is:—

1. In a shaft governor, the combination of a rotating carrier; a ring shaped centrifugal 100 weight pivotally mounted on the carrier and encircling the axis of the carrier; a centripetal element opposed to the weight and an eccentric actuated by the weight.

2. In a shaft governor, the combination of a rotating carrier having a hub; a ring shaped centrifugal weight pivotally mounted on the carrier and encircling the hub; a centripetal element opposed to the weight; and an eccentric actuated by the weight. 110

3. In a shaft governor, the combination of a rotating carrier; a centrifugal weight mounted on the carrier; a centripetal element opposed to the weight; an eccentric; a swinging mounting for the eccentric; a connection between the mounting and the weight; and a pivotal support for the mounting between the connection and the eccentric.
- 10 4. In a shaft governor, the combination of a rotating carrier; a centrifugal weight mounted on the carrier; a centripetal element opposed to the weight; an eccentric; a swinging mounting for the eccentric; a connection between the mounting and the weight; a pivotal support for the mounting between the connection and the eccentric; and an eccentric strap on the eccentric, the weight of the eccentric and parts thereon 20 balancing the centrifugal weight as to gravity.
- 15 5. In a shaft governor, the combination of a rotating carrier; a ring shaped centrifugal weight pivotally mounted on the carrier and encircling the axis of the carrier; a centripetal element opposed to the weight; an eccentric; a swinging mounting for the eccentric; a connection between the mounting and the weight; and a pivotal support for the 25 mounting between the connection and the eccentric.
- 30 6. In a shaft governor, the combination of a rotating carrier; a centrifugal weight pivotally mounted on the carrier; a centripetal element opposed to the weight; an eccentric; a swinging mounting for the eccentric; a sliding and pivotal connection between the swinging mounting and the weight; and a pivotal support for the swinging mounting.
- 40 7. In a shaft governor, the combination of a rotating carrier; a weight pivotally mounted on the carrier; a centripetal element opposed to the weight; an eccentric; a swinging mounting for the eccentric; a connection between the mounting and the weight; a pivotal support for the eccentric between the connection and the eccentric; and an eccentric rod actuated by the eccentric, the throw of the eccentric being arranged relatively to the pivotal support to 50 make the axis of the pivotal support pass the line of strain of the eccentric rod relatively to the eccentric with the eccentric in the faster portions of its throw relatively to the rod.
- 55 8. In a shaft governor, the combination of a rotating carrier; a ring shaped centrifugal weight pivotally mounted on the carrier and encircling the axis of the carrier; a centripetal element opposed to the weight; an eccentric; a swinging mounting for the eccentric; a connection between the mounting and the weight; a pivotal support for the eccentric between the connection and the eccentric; and an eccentric rod actuated by the eccentric, the throw of the eccentric being arranged relatively to the pivotal support to 60 make the axis of the pivotal support pass the line of strain of the eccentric rod relatively to the eccentric with the eccentric in the faster portions of its throw relatively to the rod.
- 65 In testimony whereof I have hereunto set my hand in the presence of two subscribing witnesses.
- 70 HAROLD F. SHEPHERD.
